(57) **CLAIM**

The ornamental design for a timing device, as shown and described.

DESCRIPTION

FIG. 1 is a front view of the timing device according to the present invention;

FIG. 2 is a top view of the timing device according to FIG. 1;

FIG. 3 is a bottom view of the timing device according to FIG. 1;

FIG. 4 is back view of the timing device according to FIG. 1;

FIG. 5 is a view taken from the right side of FIG. 1;

FIG. 6 is a view taken from the left side of FIG. 1; and,

FIG. 7 is a perspective view of the timing device according to FIG. 1.
